H. A. BRAMAN.

FIRE EXTINGUISHER.

APPLICATION FILED JAN. 13, 1920. RENEWED NOV. 30, 1920.

1,366,630.

Patented Jan. 25, 1921.

UNITED STATES PATENT OFFICE.

HAROLD A. BRAMAN, OF PROVIDENCE, RHODE ISLAND.

FIRE-EXTINGUISHER.

1,366,630.

Specification of Letters Patent. Patented Jan. 25, 1921.

Application filed January 13, 1920, Serial No. 351,139. Renewed November 30, 1920. Serial No. 427,460.

To all whom it may concern:

Be it known that I, HAROLD A. BRAMAN, a citizen of the United States of America, residing at Providence, in the county of 5 Providence and State of Rhode Island, have invented certain new and useful Improvements in Fire-Extinguishers, of which the following is a specification.

The object of my invention is to provide 10 a simply constructed fire extinguisher which can be installed at a minimum cost.

A further object of my invention is to provide a fire extinguisher which is caused to automatically distribute a fire extinguisher fluid over a relatively large area 15 when the fluid within the extinguisher forces open a valve or closure under the influence of heat.

Other and further objects and advantages 20 will be in part described and in part obvious as the specification is proceeded with.

In the drawings wherein I have illustrated a preferred embodiment of my invention the single figure is a longitudinal 25 sectional view of the invention.

Referring to the drawings the numeral 1 designates a liquid tight and air tight metallic container of any suitable shape, preferably cylindrical and preferably formed 30 with a conical shaped bottom 2. The container 1, which is adapted to hold a highly volatile fire extinguishing fluid is adapted to be detachably bolted to the ceiling of a building by means of brackets 3.

Bolted to the lower end of the container 35 1 is a cap plate 4 apertured as at 5 to receive the tapered or conical portion 6 of a valve or closure 7. The valve 7 is tapered as shown, to snugly seat against the walls 40 of the opening 5 and is provided with a shoulder or flange 8 adapted to seat a cork washer or other packing 9 the upper face of which bears against the cap plate 4 to insure a liquid and air tight joint between 45 these parts. The valve 7 is normally held in closed position by means of a frangible plate 10 of glass or the like hinged as at 39 to a lug 11 integrally formed on and depending from the cap plate 4. This frangible plate 10 is normally held in the position 50 illustrated in the drawings by means of a preferably fusible link 12 looped at its upper and lower ends respectively over an extension 13 formed on the cap plate 4 and

the free edge 14 of the hinged plate 10, the latter being thus held in tight engagement with the protuberance or fulcrum 15 formed on said valve 11. It will be noted that the protuberance 15 has a knife edge, the purpose of which will be presently described. 55

A hollow perforated liquid distributer 16 is mounted within the container 1 by means of a stem 17, slidably guided in a spider 18 in turn bolted to the inner face of the container walls as at 19. The distributer is 60 normally spring pressed against the inner face of valve 7 by a coil spring 20 engaging at opposite ends the spider 18 and distributer 16 as will be readily apparent from an inspection of the drawing.

In practice a highly volatile liquid which will not corrode metal or injure fabrics and the like and which is adapted to give off a heavier than air gas when exposed to air, is placed in the container 1, and the latter is then attached to the ceiling of a building. It will be understood that the number of containers to be employed will be regulated according to the number of cubic feet of space to be protected, the capacity of 75 the container and the fire extinguishing qualities of the liquid employed.

When a fire occurs in a room or building equipped with my invention the rise in temperature caused by a fire quickly expands the liquid in the container 1, thereby causing the valve 7 to be forced outwardly against the frangible plate 10. The knife edge of the protuberance 15 will cause the plate 10 to break when the pressure in the 80 container reaches a predetermined degree (it being understood that the plate 10 can be made of any desired strength) thus permitting the valve 7 to be forced outwardly from the opening 5. Simultaneously with the 85 opening of the valve 7 the distributer is forced outwardly through the opening 5 until this movement is arrested by the flange 30 coming in contact with the cap plate 4. Preferably a cork or other packing washer 1 90 22 effects a tight joint between said flange and cap plate. The liquid fire extinguishing medium within the container will now be forced under its own weight outwardly through the perforations 23 in a manner 95 readily understood. The ejection of the fire extinguishing liquid is also facilitated by virtue of the pressure generated within the 100 105

container by the action of the heat from the conflagration and the liquid will as a result be sprayed over a considerable area.

Any suitable means (not shown) may be provided for refilling the containers, but the latter will preferably be detached and shipped to the manufacturer for this purpose.

Where the link 12 is of fusible material 10 the operation of the extinguisher will be doubly sure. However, I do not depend upon the fusibility of the link 12 to release the valve 7 but rely entirely upon the pressure within the container and the knife edge 15 of the protuberance 15, to cause the plate 10 to break at the proper time.

If desirable the distribution of the fire extinguishing fluid may be facilitated by the use of compressed air within the container.

20 What I claim is:

1. In a device of the character described, a container for fire extinguishing liquid, said container having an opening in its bottom wall, a valve for said opening, and a member 25 of readily frangible material normally bearing against said valve to hold the same in said opening, said member being adapted to

break and release said valve when the liquid in said container exerts a predetermined pressure.

2. A fire extinguisher comprising a container for a fire extinguishing fluid, said container having an opening in its lower portion, a closure for said opening having a knife edge, a frangible member bearing against said knife edge for maintaining said closure in said opening, whereby said frangible member will be broken when the liquid in said container exerts a predetermined pressure.

3. A fire extinguisher comprising a container for fire extinguishing fluid, said container having an outlet opening, a closure therefor, means for normally maintaining said closure in said opening, including a frangible member adapted to be broken when the liquid in said container reaches a predetermined pressure.

In testimony whereof I affix my signature in presence of two witnesses.

HAROLD A. BRAMAN.
